(57) **CLAIM**

I claim the ornamental design for an oblique-impact protection layer with pattern, as shown and described.

DESCRIPTION

FIG. 1 shows a top view of an oblique-impact protection layer with pattern, showing my new invention;

FIG. 2 shows a bottom view thereof;

FIG. 3 shows a left view thereof;

FIG. 4 shows a right view thereof;

FIG. 5 shows a front view thereof;

FIG. 6 shows a back view thereof;

FIG. 7 shows a top perspective view thereof; and,

FIG. 8 shows a bottom perspective view thereof.

The shade lines in the figures show contour and do not represent surface ornamentation. The broken lines depict the boundary of the claimed design and form no part thereof.
